UNITED STATES PATENT OFFICE.

JAMES L. MCPHERSON, OF CAMDEN, NEW JERSEY.

ATTACHMENT FOR BEDS.

1,046,479.

Specification of Letters Patent. Patented Dec. 10, 1912.

Application filed June 3, 1912. Serial No. 701,133.

To all whom it may concern:

Be it known that I, JAMES L. MCPHERSON, a citizen of the United States, residing at Camden, in the county of Camden and State of New Jersey, have invented certain new and useful Improvements in Attachments for Beds, of which the following is a specification.

My invention relates to improvements in 10 attachments for beds, the object of the invention being to provide a table adapted to support articles in convenient reach of a person while in bed, and so connect the table to the bed and so construct the same 15 that the table may be adjusted to any position desired in accordance to the use to which it is put.

A further object is to provide an improved clamp which may be quickly operated to clamp the side angle of an ordinary metal bed, and securely hold the table in position.

With these and other objects in view, the invention consists in certain novel features 25 of construction and combinations and arrangements of parts, as will be more fully hereinafter described and pointed out in the claims.

In the accompanying drawings: Figure 30 1, is a view partly in elevation and partly in section illustrating my improvements secured to the angle side bar of a bed. Fig. 2, is a fragmentary plan view of the table. Fig. 3, is a view in longitudinal section 35 through the clamp, and Fig. 4, is a view in longitudinal section on an enlarged scale through the upper end of the table supporting tube illustrating its connection with the table.

40 1, represents the side angle bar of an ordinary metal bed. To this angle bar 1, my improved clamp is adapted to be secured, and comprises two members 2 and 3. These members 2 and 3 both consist of relatively 45 heavy metal strips, the member 2 bent at one end forming a hook 4 adapted to engage the inner edge of the angle bar 1. The other end of member 2 is bent downwardly forming a tongue 5, the latter having a screw-threaded opening 6 for the reception of a thumb screw 7. The inner end of this thumb screw has a swiveled connection with a depending tongue 8 on member 3. This member 3 is bent in rectangular form as indicated with its upper face positioned 55 against the under face of member 2, and

said members held in this relationship by means of a metal strap 9 which projects around both of the members. The inner end of member 3 is adapted to bear against the outer face of the angle bar 1, and the upper and lower bars of said member 3 are provided with registering openings 10, through which a tubular upright 11 projects. This upright 11 also extends through a slot 12 in member 2, and is held against vertical movement by means of a collar 13 securely clamped to the upright by a set screw 14. This collar 13 may be adjusted vertically on the upright 11 so as to regulate the position of the latter.

On the upper end of upright 11, an inverted cup shaped cap 15 is positioned, and is provided at one side with an integral enlargement 16 having a circular series of 75 radially positioned teeth 17 thereon. These teeth 17 are adapted to engage between corresponding teeth in an enlargement 18 on a V-shaped bracket 19, and to this V-shaped bracket 19, a table 20 is secured by screws 80 21. The enlargements 18 and 16, cap 15, and upright 11 are all provided with registering openings for the accommodation of a bolt 22 having a head at one end, and a thumb nut 23 at its other end, whereby the 85 said parts are clamped together.

To change the angle of the table, it is simply necessary to unscrew the thumb nut sufficiently to permit the teeth of enlargements 16 and 18 to disengage when the table 90 may be turned to the desired angle and secured in this angle, when the enlargements are drawn together by screwing home the nut.

The table 20 around its edge on its upper 95 face, is made with a bead or flange 24 which is desirable especially when the device is positioned at an angle, as this flange or bead forms a ledge to support a book.

While in Fig. 1, the table is shown projecting away from the bed in normal use, when the articles are positioned thereon, this table will be swung over the bed and be positioned at the proper angle in accordance with its use. The clamp may be readily connected and disconnected from the bed by turning the bolt 7, and when positioned on the bed, the parts will be rigidly held.

Various slight changes might be made in the general form and arrangement of parts 110 described without departing from my invention, and hence I do not limit myself to

the precise details set forth, but consider myself at liberty to make such changes and alterations as fairly fall within the spirit and scope of the appended claims.

5 Having thus described my invention, what I claim as new and desire to secure by Letters Patent is:

1. A device of the character described, comprising an upright, a table on the upright, a bed clamp comprising two members slidably upon each other and having registering openings therethrough for the reception of said upright, a hook on one member adapted to engage the inner edge of a bed side bar, and a screw constructed to move the other member against the outer face of said bed side bar, substantially as described.

2. A device of the character described, comprising a table supporting upright, a bed clamp consisting of two members, one

member having a hook at one end, and a depending tongue at the other, said member having a slot therein, the other member of general rectangular form, and having registering openings in its top and bottom portion, a strip connecting the two members, a screw engaging in a threaded opening in said tongue and swiveled to the last mentioned member, said upright positioned through the slot and the registering openings, and a collar adjustably secured on the upright and regulating the vertical position of the upright.

25 In testimony whereof I have signed my name to this specification in the presence of two subscribing witnesses.

30 JAMES L. McPHERSON.
